SUSPENSION OF INCLINED CONVEYERS IN
HARVESTING MACHINES

Karl-Heinrich Schulze, Mannheim, Germany, assignor to Heinrich Lanz Aktiengesellschaft, Mannheim, Germany

Application August 3, 1938, Serial No. 222,782
In Germany November 4, 1937

8 Claims. (Cl. 198—165)

The present invention relates to the arrangement of the elevator conveyer in harvesting, especially mowing and binding machines and particularly to a method of mounting and suspending the upper inclined conveyer to the main frame of machines of the type set forth.

An object of the present invention resides in the provision of suspension means for the upper inclined conveyer in mowing and binding machines whereby the passage formed between the upper and lower conveyer is open on one side to provide for any length of harvested goods and whereby no structural elements are needed which project beyond the width of the conveyers and unduly increase the space requirements of the machine. With the construction according to the present invention an unobstructed passage of the mowed material from the substantially horizontal platform up to the binding table is assured and the total width of the mowing and binding machine is held at a minimum so that it can be moved through narrow streets and congested areas without difficulty.

An object of the present invention resides in the provision of a support system for the upper elevator of mowing and binding machines and the like whereby one bearing of the upper roll of said elevator is supported in the front head piece and the lower part of the elevator is movably supported in a slot of the elevator wall and the elevator is swingably supported by means of one or a plurality of outriggers the ends of which outriggers are provided with flanges or the like which carry the other bearing of the elevator roll and also the rods for positioning the elevator. The outriggers may be rigidly connected with the front head piece, with the elevator wall, with the main frame or with another suitable part of the machine.

A further object of the present invention resides in the provision of a support for the upper elevator in mowing and binding machines or the like whereby the upper shaft or roll of the elevator is utilized as outrigger. Thereby one end of the upper shaft rests in broad bearings of the front head piece and the other end rotates in a guide bearing which is supported by suitable struts.

Further and other objects of the present invention will be hereinafter set forth in the accompanying specification and shown in the drawings which, by way of illustration, show what I now consider to be a preferred embodiment of my invention.

In the drawings:

Figure 1 is an isometric view of the horizontal conveyer and the elevator conveyers of a harvesting machine according to the present invention.

Figure 2 is a part sectional front view of the parts shown in Figure 1.

Figure 3 is a side view of the parts shown in Figs. 1 and 2.

Figure 4 is a part sectional front view of a modified elevator conveyer support structure according to the present invention.

Figure 5 is a top view of the structure shown in Figure 4.

Like parts are designated by like letters in all figures of the drawings.

Referring more particularly to Figures 1 to 3, *a* designates the main frame of the machine to which the platform conveyer *b* and the lower elevator conveyer *c* is mounted. The upper roll *g* of the upper elevator conveyer *f* rests with one end in the front head piece *h*; the lower end of the upper elevator conveyer is movably connected with the elevator side wall *t* by means of a peg *s'* which moves in slot *s* of wall *t*. To the head part *h* a tubular outrigger *i* is connected which extends over the whole width of the elevator. The free end of outrigger *i* carries a flange *k* to which the outer bearing *l* for the upper elevator roll *g* is connected. The upper elevator *f* is swingably hung in between the front head piece *h* and the flange *k* of the outrigger and is also suspended by means of a link *o* which hangs in a slot *m* of the flange *k* and is hooked to the ear piece *p* which projects from the lower part of the side cover plate *t'* of the elevator. A flange *q* is provided on the tubular outrigger *i* to which flange the lower ends of the connecting means or tie rods *r* are connected; the other ends of said tie rods are connected with the head piece *h* so that the tie rods *r* prop the outrigger against the head piece. By changing the active length of the tie rods *r*, for example, by the manipulation of the fastening nuts *q'* and/or *h'* the position of the outrigger *i* and thereby of the upper elevator *f* can be changed.

Figures 4 and 5 illustrate a modification of the present invention in which the upper elevator roll *u* is used to serve also as outrigger. A long bearing *v* is provided on the head piece *h* for supporting one end of roll *u*. The free or outer end of the roll rotates in a bearing *x* which is carried by means of the flange *y* which flange is propped to head piece *h* by means of the braces *z*. A cantilever member *u'* may be provided extend-

ing through bearing member *v* and supporting bearing *x*.

In both embodiments of the present invention the harvested material is transported by means of the platform conveyer *b* into the space in between the elevator conveyers *c* and *f* and is transported by the latter in a continuous and unobstructed flow towards the binding table. The upper elevator *f* swinging about its upper support and being guided by the slot *S* in wall *t* automatically adjusts the space in between the elevators *c* and *f* to the volume of the harvested material. The upper end of the link *o* moves in slot *m* of flange *k* so that there is no obstruction to the swinging motion of the elevator *f*.

With the outrigger or cantilever suspension construction for the upper elevator according to the present invention all obstructions to the free passage of long harvested material which may project far out of the rear side of the elevator are definitely avoided. Furthermore the lower part of the elevator does not take part in the support of the upper part. The position of the free end of the outrigger and thereby of the elevator can easily be adjusted. The elevator can easily be made swingable about its upper roll whereby adjustment of the elevator according to the volume of the harvested material is conveniently accomplished.

While I believe the above described embodiments of my invention to be preferred embodiments, I wish it to be understood that I do not desire to be limited to the exact details of design and construction shown and described, for obvious modifications will occur to a person skilled in the art.

I claim:

1. A suspension system for the upper inclined conveyer in harvesting machines and the like having a main body, said system comprising an outrigger having one end connected in cantilever manner to said main body, said outrigger swingably carrying said conveyer.

2. A suspension system for the upper inclined conveyer in harvesting machines and the like having a main body, said system comprising a tubular outrigger having one end connected in cantilever manner to said main body, said outrigger swingably carrying said conveyer.

3. A suspension system for the upper inclined conveyer in harvesting machines and the like having a main machine body, said conveyer having an upper roll, said system comprising an outrigger having a free end and an end which is connected to said machine body, a flange member connected to the free end of said outrigger, said upper roll having an end which is supported

in said machine body and another end which is supported by said flange member.

4. A suspension system for the upper inclined conveyer in harvesting machines and the like having a main machine body, said conveyer having an upper roll, said system comprising an outrigger having a free end and an end which is connected to said machine body, a flange member connected to the free end of said outrigger, said upper roll having an end which is supported in said machine body and another end which is supported by said flange member, and connecting means interconnecting said flange means and said machine body for holding said outrigger in a desired position.

5. A suspension system for the upper inclined conveyer in harvesting machines and the like having a main machine body, said conveyer having an upper roll, said system comprising an outrigger having a free end and an end which is connected to said machine body, a flange member connected to the free end of said outrigger, said upper roll having an end which is supported in said machine body and another end which is supported by said flange member, and adjustable bracing means interconnecting said flange means and said machine body for holding said outrigger in adjustable position.

6. A suspension system for the upper inclined conveyer in harvesting machines and the like having a frame, said conveyer having an upper roll and being swingable about said roll, said system comprising an outrigger extending in cantilever manner from said frame and carrying said upper roll.

7. A suspension system for the upper inclined conveyer in harvesting machines and the like having a main body, said system comprising a cantilever member projecting from and being rigidly connected with said body, and a cylindrical roll substantially surrounding said member and being rotatably supported by said body and said member and forming the upper roller of said upper inclined conveyer and swingably supporting said conveyer.

8. A suspension system for the upper inclined conveyer in harvesting machines and the like having a main body, said system comprising an outrigger connected at one end in cantilever manner with said main body and including a roll forming the upper roller of and swingably supporting said upper inclined conveyer and having one end rotatably connected with said main body, and connecting means operatively connecting the other end of said roll with said main body.

KARL-HEINRICH SCHULZE.
